(57) **ABSTRACT**

A self-contained medication apparatus which includes a first container having a first semi-spherical portion, and a second container having a second semi-spherical portion and a cylindrical portion formed with the second semi-spherical portion. At least one type of medication disposed within the first container, such as one or more pills, and a consumable liquid disposed within the second container. The first container is pivotally connected to the second container by a hinge member between an open position and a closed position. A first seal is connected to the first semi-spherical portion of the first container, and a second seal is connected to the cylindrical portion of the second container. The first seal and the second seal are removed to allow the medication to be removed from the first container and allow access to the consumable fluid such that the medication and the consumable fluid may be ingested.

FIG. 2

FIG. 1

FIG. 6

FIG. 5

1

SELF-CONTAINED MEDICATION APPARATUS

FIELD OF THE INVENTION

The present invention relates to a single-use medication apparatus which is disposable, where the apparatus has two containers, one of which contains medication, and another of which contains fluid, such as water.

BACKGROUND OF THE INVENTION

It is common for travelers to take medication on trips so the medication is available when needed. Some types of medication is prescription, other types of medication are available over the counter. Many types of over the counter drugs are sold in pill form, and as many as a few hundred pills are stored in a container, such as a bottle. However, there are times when it is inconvenient to carry an entire bottle of pills all the time, especially when only one or two pills may be needed. Furthermore, most pills are taken with water or some other type of consumable fluid, which may not be readily available when traveling. Furthermore, when traveling by airplane, there are limits to the amount of liquid which may be brought to the airport and taken on a plane. It is commonplace for only one or two doses of medication to be necessary throughout the day, therefore making it unnecessary to carry an entire bottle of pills. Additionally, if only one or two doses of medication are necessary, then it may not be cost-effective to buy an entire bottle of pills and water.

Accordingly, there exists a need for a device which is usable for carrying medication in pill form as well as a consumable fluid, provides a single-dose of the medication, and is disposable.

SUMMARY OF THE INVENTION

The present invention is directed to a self-contained medication apparatus. More specifically, the present invention is a self-contained medication apparatus which includes a first container having a first semi-spherical portion, and a second container having a second semi-spherical portion and a cylindrical portion formed with the second semi-spherical portion. At least one type of medication is disposed within the first container, such as one or more pills, and a consumable liquid is disposed within the second container.

The first container is pivotally connected to the second container by a hinge member between an open position and a closed position. The hinge member has a locking feature which is operable for locking the first container and the second container in the open position.

The present invention also includes a locking mechanism for providing a snap-fit connection between the first container and the second container when the first container and the second container are in the closed position.

A first seal is connected to the first semi-spherical portion of the first container, and a second seal is connected to the cylindrical portion of the second container. The first seal has a first tab which is pulled to remove the first seal, allowing access to the medication inside the first container. The second seal has a second tab which is pulled to remove the second seal from the second container, allowing access to the consumable fluid such that the medication and the consumable fluid may be ingested.

Further areas of applicability of the present invention will become apparent from the detailed description provided hereinafter. It should be understood that the detailed description

2

and specific examples, while indicating the preferred embodiment of the invention, are intended for purposes of illustration only and are not intended to limit the scope of the invention.

5 BRIEF DESCRIPTION OF THE DRAWINGS

The present invention will become more fully understood from the detailed description and the accompanying drawings, wherein:

- 10 FIG. 1 is a perspective view of a self-contained medication apparatus, according to the present invention;
- 15 FIG. 2 is a perspective view of a self-contained medication apparatus in a partially open position, according to the present invention;
- 20 FIG. 3 is a perspective view of a self-contained medication apparatus in a fully open position, according to the present invention;
- 25 FIG. 4 is a perspective view of a self-contained medication apparatus in a fully open position, with one of the seals partially removed, according to the present invention;
- 30 FIG. 5 is a perspective view of a self-contained medication apparatus in a fully open position, with one of the seals fully removed, according to the present invention;
- 35 FIG. 6 is a perspective view of a self-contained medication apparatus in a fully open position with both seals removed, according to the present invention;
- 40 FIG. 7A is a partial sectional side view of a self-contained medication apparatus in a fully open position with both seals removed, according to the present invention; and
- 45 FIG. 7B top view of a self-contained medication apparatus in a fully open position with both seals removed, according to the present invention.

DETAILED DESCRIPTION OF THE PREFERRED EMBODIMENTS

The following description of the preferred embodiment(s) is merely exemplary in nature and is in no way intended to limit the invention, its application, or uses.

- 40 An embodiment of a self-contained medication apparatus is shown in the Figures generally at 10. The apparatus 10 includes at least two containers, a first container, generally shown at 12, and a second container, generally shown at 14. The second container 14 has a substantially cylindrical portion 16. The first container 12 is made of a first semi-spherical portion 18 which is pivotally connected to the cylindrical portion 16. There is also a second semi-spherical portion 20 formed as part of the second container 14, and connected to the cylindrical portion 16.
- 45 The first container 12 is connected to the second container 14 by a hinge member 22 and a locking mechanism, shown generally at 24. The locking mechanism 24 provides a snap fit connection between the first container 12 and the second container 14 such that the first container 12 is pivotable relative to the second container 14 about the hinge member 22, and the locking mechanism 24 is operable to connect the containers 12,14 together such that the containers 12,14 do not move relative to one another.
- 50 The locking mechanism 24 includes a divot 26 formed as part of the cylindrical portion 16, an overhanging lip 28 formed as part of the first semi-spherical portion 18, and an angled lip 54 formed as part of the cylindrical portion 16. When the apparatus 10 is in the closed portion, as shown in FIG. 1, the overhanging lip 28 has an angled portion which includes a contact surface 56 which contacts a corresponding contact surface 58 of the angled lip 54, forming an interference fit, and securing the apparatus 10 in the closed portion.
- 55
- 60
- 65

When in the closed position, a bottom surface **60** of the overhanging lip **28** is in contact with a ledge **72** formed as part of the cylindrical portion **16**. When it is desired to change the apparatus **10** to the open position, as shown in FIGS. 3-7B, a force is applied to the bottom surface **60** of the overhanging lip **28** in the area of the divot **26** to deflect the overhanging lip **28** and the angled lip **54**, allowing the contact surfaces **56,58** to rub against one another, displacing the overhanging lip **28** from the angled lip **54**, and therefore allowing the first container **12** to be pivoted relative to the second container **14** about the hinge member **22**. The divot **26** allows easy access to the bottom surface **60** of the overhanging lip **28**.

When moved to the open position, the hinge member **22** maintains the position of the first container **12** at one-hundred-eighty degrees relative to the position of the first container **12** when in the closed position, shown by the angle **30**. This is achieved by a locking feature, shown generally at **32**, formed as part of the hinge member **22**. The locking feature **32** is formed by the shape of the hinge member **22**. There is a first deflection portion **34** and a second deflection portion **36**, and when the first container **12** is pivoted relative to the second container **14** toward the open position, the deflection portions **34,36** lock the first container **12** in place, as shown in FIGS. 3-6.

Located in the first semi-spherical portion **18** is a first seal **38**, and located in the cylindrical portion **16** is a second seal **40**. The first seal **38** is mounted on a lip **42** formed as part of the first semi-spherical portion **18**, and is connected to the lip **42** by an adhesive. The second seal **40** is mounted on part of a top surface **70** of the angled lip **54** formed as part of the cylindrical portion **16**, and is also attached to the top surface **70** by an adhesive. The second seal **40** connected to the top surface **70** and the first seal **38** connected to the lip **42** do not interfere with the operation of the locking mechanism **24**. While the seals **38,40** in this embodiment are made of a thin, flexible, plastic material, it is within the scope of the invention that other types of materials may be used, such as a thin foil aluminum, a clear plastic, or any other suitable material which functions to separate the first container **12** from the second container **14**.

The first seal **38** also has a first tab **46**, and the second seal **40** has a second tab **48**. The seals **38,40** separate the internal volumes of the containers **12,14** from one another. Medication **50** is stored in the first container **12**, and a consumable liquid **52**, which in this embodiment is water, is stored in the second container **14**.

The apparatus **10** is typically in the stowed position, and when it is desired to consume the medication **50**, the user simply changes the apparatus **10** such that the first container **12** is locked in the open position. Essentially, the user applies force to the bottom surface **60** to deflect the overhanging lip **28** and the angled lip **54**, and allow the first container **12** to pivot relative to the second container **14** as described above, until the first container **12** is locked in the open position. The locking feature **32** maintains the position of the first container **12** in the open position, and prevents the first container **12** from unintentionally moving back to toward the closed position. The first tab **46** is then pulled with enough force to overcome the force of the adhesive connecting the first seal **38** to the lip **42**, best shown in FIG. 4, to remove the first seal **38** and allow for the medication **50** to be removed from the first container **12** and consumed. The second tab **48** is then pulled with enough force to overcome the force of the adhesive connecting the second seal **40** to the top surface **70**, thereby removing the second seal **40** from the second container **14**, allowing the water **52** to be consumed. The apparatus **10** of the present invention provides the advantage of not requiring

a surface for supporting either of a bottle of pills or a bottle of water while the bottle of pills or bottle of water is opened, allowing for two hands to be used to operate the apparatus **10** while walking or performing some other task.

In the alternative both seals **38,40** may be removed prior to consuming the medication **50** or water **52**, and the user then may consume the medication **50** and the water **52** in the conventional manner. The apparatus **10** provides a simple, yet effective way of traveling with medication, without traveling with an entire bottle of medication, and a separate bottle of water to use when consuming the medication. Each container **12,14** is made of a disposable and recyclable material, so after consuming the medication and the water, the entire apparatus **10** may be deposited in a recycle bin. Once the seals **38,40** have been removed, the seals **38,40** may be placed back inside the apparatus **10** (which snaps shut because of the locking mechanism **24**), allowing the user to carry the apparatus **10** until a recycling bin is found.

In this embodiment, the overall length of the apparatus **10** is about **3.5** inches, with the first container **12** having a length **62** of about **0.5** inches and the second container **14** having a length **64** of about **3.0** inches. The diameter **66** of the containers **12,14** is about **1.25** inches. Additionally, the wall thickness **68** of the apparatus **10** is about **0.03** inches. The apparatus **10** is small enough to only contain the maximum amount of water allowed through airport security (about **2.7** ounces, which is **0.3** ounces less than the maximum of **3.0** ounces allowed through airport security), which would allow the apparatus **10** to be taken on an airplane when traveling. However, in alternate embodiments, the apparatus **10** may be made of different sizes to contain different amounts of medication **50** and different amounts of water **52**.

The description of the invention is merely exemplary in nature and, thus, variations that do not depart from the essence of the invention are intended to be within the scope of the invention. Such variations are not to be regarded as a departure from the spirit and scope of the invention.

What is claimed is:

1. A self-contained medication apparatus, comprising:
a first container;
a first seal being part of said first container; a second container pivotally connected to said first container such that said first container and said second container are operable to be moved between an open position and a closed position;
a second semi-spherical portion formed as a lower part of said second container such that said self-contained medication apparatus has a rounded bottom surface;
a second seal being part of said second container, said first seal and said second seal separating said first container and said second container;
a hinge member connecting said first container and said second container such that said first container and said second container are movable between an open position and a closed position, wherein said hinge member is a locking hinge to maintain a flat open position of said hinge member and hold said first container and second container in said open position; a type of medication disposed within said first container; and a consumable liquid disposed within said second container, wherein said second container is operably sized to contain a maximum amount of consumable liquid of not more than about **2.7** ounces;
wherein said first seal is removed from said first container and said second seal is removed from said second container, allowing said medication and said consumable liquid to be consumed; wherein said self-contained

5

medication apparatus is a single-use medication apparatus which is disposable and formed of recyclable material;

a locking mechanism provides a connection between said first container and said second container when said first container and said second container are in said closed position; said locking mechanism further comprising: an overhanging lip formed as part of said first container; an angled portion formed as part of said overhanging lip, said angled portion having a first contact surface; an angled lip formed as part of said second container, said angled lip having a second contact surface in contact with said first contact surface when said first container and said second container are in said closed position; and a bottom surface formed as part of said overhanging lip, said bottom surface operable for being selectively in contact with a ledge formed as part of said second container when said first container and said second container are in said closed position; a first deflection portion and a second deflection portion, wherein said first deflection portion and said second deflection portion lock said first container in said open position at one-hundred-eighty degrees relative to the position of said first container when in said closed position.

5

2. The self-contained medication apparatus of claim 1, said first container further comprising:

a first semi-spherical portion; and
a lip formed as part of said first semi-spherical portion, said first seal being attached to said lip.

30

3. The self-contained medication apparatus of claim 2, further comprising a first tab connected to said first seal, wherein said first tab is pulled to remove said first seal from said lip, exposing said medication located in said first container.

35

4. The self-contained medication apparatus of claim 1, said second container further comprising:

a cylindrical portion connected to said second semi-spherical portion; and
a top surface formed as part of said cylindrical portion, said second seal connected to said top surface.

40

5. The self-contained medication apparatus of claim 4, further comprising a second tab connected to said second seal, wherein said second tab is pulled to remove said second seal from said top surface, exposing said consumable liquid located in said second container.

45

6. The self-contained medication apparatus of claim 1, said locking mechanism further comprising:

a divot formed as part of said second container, said divot creating a contactable area having a wall thickness of material that is less than the remainder of the second container wall thickness;

50

wherein pressure is applied to said bottom surface in an area in proximity to said divot to cause said overhanging lip and said angled lip to deflect, said first contact surface to rub against said second contact surface, and said bottom surface to lift away from said ledge, separating said first container from said second container, allowing said first container and said second container to be moved to said open position.

55

7. The self-contained medication apparatus of claim 1, further comprising a locking feature including said first deflection portion and said second deflection portion operable for locking said first container in said open position.

60

8. A self-contained medication apparatus, comprising:
a first container;
a second container;

6

a second semi-spherical portion formed as a lower part of said second container such that said self-contained medication apparatus has a rounded bottom surface; a hinge member pivotally connecting said first container and said second container such that said first container and said second container are movable between an open position and a closed position, wherein said hinge member is a locking hinge to maintain a flat open position of said hinge member and hold said first container and second container in said open position;

a locking feature operable for locking said first container and said second container in said open position, said locking feature being part of said hinge member; a locking mechanism provides a connection between said first container and said second container when said first container and said second container are in said closed position; said locking mechanism further comprising: an overhanging lip formed as part of said first container; an angled portion formed as part of said overhanging lip, said angled portion having a first contact surface; an angled lip formed as part of said second container, said angled lip having a second contact surface in contact with said first contact surface when said first container and said second container are in said closed position; and a bottom surface formed as part of said overhanging lip, said bottom surface operable for being selectively in contact with a ledge formed as part of said second container when said first container and said second container are in said closed position; a first deflection portion and a second deflection portion, wherein said first deflection portion and said second deflection portion lock said first container in said open position at one-hundred-eighty degrees relative to the position of said first container when in said closed position;

a first seal, said first seal being part of said first container; a second seal, said second seal being part of said second container; a medication disposed in said first container such that when said first seal is removed from said first container, said medication is able to be removed and consumed; and

a consumable liquid disposed in said second container such that when said second seal is removed from said second container, said consumable liquid is able to be removed and consumed, wherein said second container is operably sized to contain a maximum amount of consumable liquid of not more than about 2.7 ounces;

wherein said self-contained medication apparatus is a single-use medication apparatus which is disposable and formed of recyclable material and dispenses a single dosage of medication and liquid.

9. The self-contained medication apparatus of claim 8, further comprising:

a first semi-spherical portion, said first semi-spherical portion formed as part of said first container;
a lip formed as part of said first semi-spherical portion, said first seal being disposed on said lip;
a cylindrical portion connected to said second semi-spherical portion; and
a top surface formed as part of said cylindrical portion, said second seal being disposed on said top surface;
wherein said first seal is removed from said lip, allowing said medication to be removed from said first container, and said second seal is removed from said top surface, allowing said consumable liquid to be removed from said second container.

10. The self-contained medication apparatus of claim 8, further comprising:

a first tab connected to said first seal, said first tab is pulled to remove said first seal from said lip; and a second tab connected to said second seal, said second tab is pulled to remove said second seal from said top surface.

11. The self-contained medication apparatus of claim 8, wherein said locking mechanism provides a snap-fit connection between said first container and said second container when said first container and said second container are in said closed position.

12. The self-contained medication apparatus of claim 8, said locking mechanism further comprising:

a divot formed as part of said second container, said divot creating a contactable area having a wall thickness of material that is less than the remainder of the second container wall thickness;

wherein pressure is applied to said bottom surface in an area in proximity to said divot to cause said overhanging lip and said angled lip to deflect, said first contact surface to rub against said second contact surface, and said bottom surface to lift away from said ledge, separating said first container from said second container, allowing said first container and said second container to be moved to said open position.

13. A self-contained medication apparatus, comprising: a first container having a first semi-spherical portion; a second container having a second semi-spherical portion and a cylindrical portion formed with said second semi-spherical portion such that said self-contained medication apparatus has a rounded bottom surface;

a hinge member, said first container pivotally connected to said second container by said hinge member between an open position and a closed position, wherein said hinge member is a locking hinge to maintain a flat open position of said hinge member and hold said first container and second container in said open position;

a locking feature operable for locking said first container and said second container in said open position;

a locking mechanism for providing a snap-fit connection between said first container and said second container when said first container and said second container are in said closed position;

a first seal having a first tab, said first seal connected to said first semi-spherical portion; the locking mechanism provides a connection between said first container and said second container when said first container and said second container are in said closed position; said locking mechanism further comprising: an overhanging lip formed as part of said first container; an angled portion formed as part of said overhanging lip, said angled portion having a first contact surface; an angled lip formed as part of said second container, said angled lip having a second contact surface in contact with said first contact surface when said first container and said second container are in said closed position; and a bottom surface

5

55

ledge formed as part of said second container when said first container and said second container are in said closed position; a first deflection portion and a second deflection portion, wherein said first deflection portion and said second deflection portion lock said first container in said open position at one-hundred-eighty degrees relative to the position of said first container when in said closed position;

a second seal having a second tab, said second seal connected to said cylindrical portion;

at least one type of medication disposed within said first container; and

a consumable liquid disposed within said second container, wherein said second container is operably sized to contain a maximum amount of consumable liquid of not more than about 2.7 ounces;

wherein said first tab of said first seal is pulled to remove said first seal from said first container, allowing access to said medication, and said second tab is pulled to remove said second seal from said second container, allowing access to said consumable fluid such that said medication and said consumable fluid may be ingested,

wherein no surface is required to support or operate said self-contained medication apparatus;

wherein said self-contained medication apparatus is a sanitary pre-sealed single-use medication apparatus which is disposable and formed of recyclable material and dispenses a single dosage of medication and liquid.

14. The self-contained medication apparatus of claim 13, wherein said hinge member is connected to said first semi-spherical portion and said cylindrical portion.

15. The self-contained medication apparatus of claim 13, said locking mechanism further comprising:

a divot formed as part of said cylindrical portion, said divot creating a contactable area having a wall thickness of material that is less than the remainder of the second container wall thickness;

wherein pressure is applied to said bottom surface in an area in proximity to said divot to cause said overhanging lip and said angled lip to deflect, said first contact surface to rub against said second contact surface, and said bottom surface to lift away from said ledge, separating said first container from said second container, allowing said first container and said second container to be moved to said open position.

16. The self-contained medication apparatus of claim 13, further comprising:

a lip formed as part of said first semi-spherical portion, said first seal being connected to said lip; and

a top surface formed as part of said cylindrical portion, said second seal being connected to said top surface;

wherein said first seal and said second seal separate said first container and said second container when said first seal is connected to said lip and said second seal is connected to said top surface.
